UNITED STATES PATENT OFFICE.

JONATHAN A. HUNT, OF SALEM, MASSACHUSETTS.

ROD-GRINDING MACHINE.

Application filed August 17, 1920. Serial No. 404,110.

To all whom it may concern:

Be it known that I, JONATHAN A. HUNT, citizen of the United States, and a resident of Salem, in the county of Essex and 5 State of Massachusetts, have invented an Improvement in Rod-Grinding Machines, of which the following description, in connection with the accompanying drawings, is a specification, like characters on the 10 drawings representing like parts.

This invention relates to machines for pointing wires or rods but more particularly wires used in making talking machine needles. An object of the invention is to 15 provide a rapid machine that may readily be adjusted to compensate for wear particularly of the grinder or work-forming member or to receive work of various sizes and lengths.

20 The invention consists in the combination and arrangement of parts set forth in the following specification and particularly pointed out in the claims.

In the accompanying drawings wherein 25 is shown merely for the purpose of illustration one embodiment of the invention:

Fig. 1 is a front elevation of the machine;

Fig. 2 is a left-hand side elevation of the 30 same;

Fig. 3 is a vertical section, partly in elevation, taken on the line 3—3 of Fig. 2;

Fig. 4 shows a detail plan view of the 35 main frame, grinding wheel and housing for said grinding wheel viewed from the line 4—4 of Fig. 1;

Fig. 5 is a skeletonized plan of the raising and lowering means for the grinding wheel housing viewed from the line 5—5 40 of Fig. 1; and

Fig. 6 is a detail vertical section taken on the line 6—6 of Fig. 4 illustrating the adjusting means for the left or lower end of the work table.

45 Fig. 7 is a detail view of a portion of one of the feed wheels 33 and its saddle.

In the drawings a frame is shown for supporting the various instrumentalities of the machine. This frame preferably is of 50 box-like formation including front and back members 1 and 2 and side members 3 suitably secured together. Mounted within said frame is a casing or housing 4 adapted to contain the work-forming member herein 55 an abrasive grinding wheel 5, the latter being secured to an arbor 6 journalled in bearing

ing blocks 7, 7 at opposite sides of the grinder housing 4.

The grinding wheel 5 is provided with a concave grinding surface 8 of well known 60 form.

It is desirable that the grinding wheel be adjustable in order to compensate for the wearing down thereof and this adjustment is preferably such as to effect the movement of the axis of the wheel laterally and to maintain said axis substantially parallel with the positions previously occupied thereby. To effect this result the housing 4 within which the wheel is journalled to 70 rotate is adapted to be moved bodily in a vertical direction within the frame 3, preferably by means including screws 9, herein two, pivotally connected at their upper ends as at 10 between lugs 11 formed upon 75 said housing.

The screws 9 are guided in lugs 12 formed upon the side members 3 of the frame and vertical movement is imparted to each of said screws herein by nuts 13 constructed 80 as bevel pinions and to rotate upon the lugs 12. Each of the nuts or pinions 13 is arranged to mesh with a bevelled gear 14 (see Figs. 3 and 5) attached to a counter-shaft and journalled to rotate in suitable 85 bearings or lugs 16 projecting from the side frames 3. Secured to the opposite end of each of the counter-shafts 15 is a second bevelled gear 17 in turn meshing with the driving gear 18 attached to a common operating shaft 19, the latter arranged in bearings 20 also on the side frames 3. An operating wheel 21 is attached to said shaft 19 whereby a rotary motion may be imparted thereto by the operator. By the means 90 described it will be evident that both sides of the housing and incidentally both ends of the arbor 6 for the grinding wheel will be given simultaneous and uniform movements either up or down as the case may 95 be. It is desirable that the casing be securely held in its adjusted positions for 100 which purpose binding screws 22 are arranged to extend through slots 23 in the side frames 3 and into screw-threaded engagement with opposite portions of the housing, which portions have surfaces 24 to engage corresponding surfaces upon the inside of the frames 3.

When adjustment of the housing is desired 110 the binding screws 22 are relieved and the shaft 19 is rotated by the operating

wheel 21 to simultaneously rotate the nuts 13 through the intervening trains of gears, thus simultaneously raising or lowering the screws 9 through the lugs 12. After the desired adjustments have been made the binding screws 22 are tightened, thus securing together the adjacent portions of the housing and the frame 3.

Lateral play of the housing 4 in a direction axially of the arbor 6 during the raising and lowering of the housing is prevented herein by guide screws 25 mounted in the frames 1 and 2 so as to extend into engagement with the faces of the ribs 26 formed upon said housing. The screws 25 may, however, if desired, be adjusted to tip said housing thus throwing the axis of the grinder arbor out of parallel with its former position and this in order to vary the concave face of the grinder to make it conform with the grinding surface of the saddles hereinafter described, this adjustment being of particular advantage to overcome uniform wearing of the grinding surface of the grinder. To rotate the grinder 5 a pulley 27 is attached to one end of the arbor 6 and receives its power from any appropriate source.

The housing 4 for the grinder is preferably arranged to extend around the greater portion of the periphery of said grinder to catch grinding dust that otherwise would be thrown off thereby leaving only a relatively small peripheral opening as at 28 for the admission of the work to the face of the grinder and to prevent the discharge of dust through this opening a suitable guard is placed adjacent to the upwardly moving side of the grinder, said guard consisting of a plate 29 (see Fig. 8) the edge whereof is arranged to substantially fit the concave face of the grinder and this plate is adjustably mounted upon the housing 4 to compensate for the wearing down of the grinder.

To the lower portion of the housing 4 a pipe 30 is attached which pipe preferably communicates with a suitable blower device of a well known form therefore not shown, for removing the grinding dust from the housing. This pipe is preferably provided with a telescopic connection 31 to allow for vertical adjustment of the housing within the frame.

In machines of the character described the work is fed transversely of the face of the grinding wheel or work-forming member and preferably in substantially tangential relation thereto but at an angle to the axis of the grinder, the grinding operation being initiated upon the end of the work at a point on the circumference of the grinder in advance of the point of contact of the tangent with its circle, the end of the work being moved during the feeding operation at an angle to but toward a radial plane

passing through said point of contact. As the work, herein rods, is advanced transversely of the grinding surface of the grinding wheel its end will gradually assume the form of a point by reason of its gradual approach to said plane.

It is obviously within the scope and purpose of the invention to form either a chisel or a round point upon the ends of the rods but in the present example means for effecting the rounding of the points are provided, said means preferably including a plurality of saddles 32 and cooperating feed wheels 33. The saddles 32 have concave and herein resilient guiding surfaces 34 which coincides with the face of the grinding wheel 5. The cooperating faces of the feed wheel are likewise provided with resilient covering 35 and these conform with the faces 34 of the saddles. It is desirable at times to vary the angle of approach of the rods or work with respect to the grinding surface of the member 5 so that the taper or angle of the finished point may be long or short and in the present example this adjustment is provided for by mounting the saddles 32 and their cooperating feed wheels upon a suitable work table 36 to which lateral, longitudinal or transverse movement may be imparted to vary its relation to the work member as will hereinafter be described. The table 36 has an opening 37 through which the housing and grinding wheel are adapted to protrude in order that the work carried by said plate or saddles thereon may be brought into contact with the grinding face of said wheel.

The work table 36 is disposed at an angle to a vertical plane passing through the axis of the grinding wheel and this table is preferably pivotally mounted so that such angle may be varied from time to time. The saddles 32 are mounted upon the table 36 within the opening 37 and in such a manner that they may be adjusted longitudinally of said opening or said table, or said saddles may be rocked slightly to cause the guiding surfaces thereof to more perfectly fit or coincide with the guiding or coating surfaces of the feed wheels 33. To effect the adjustment of the saddles longitudinally of the table one side of each saddle is arranged to engage a key 38 (see Fig. 7) which key is arranged to slide with said saddle and in a groove 39 extending longitudinally of the table 36 and parallel with the opening 37. The key 38 may be attached in any appropriate manner to said saddle but as shown it extends into a groove 40 formed in said saddle. An adjusting screw 41 is secured at each side of the saddle in lugs 42 projecting laterally from opposite faces thereof (see also Fig. 3), said screws 41 being adjacent to the key 38. The screws 41 engage the upper surface of the table 36

and are held in contact therewith by screws 43 extending through the lugs 42 and into screw-threaded engagement with said table 36. Hence it will be seen that by adjusting the positions of the screws 31 in said lugs, a slight vertical adjustment may be provided for the end of the saddles at which said lugs are located and this adjustment may be fixed by the screws 43. The opposite ends of the saddles are also adjustably arranged with respect to the upper surface of the table 36 and herein by means of adjusting screws 44 having screw-threaded engagement with lateral lugs 45 on said saddles, and resting against the upper face of the table 36. Contact of said screws with said table is maintained by screws 46 which extend through said lugs 45 and into screw-threaded engagement with the table. By means of the adjusting devices just described the guiding surface of each saddle may be adjusted so as to secure the most effectual cooperation with the grinding surface of the grinding wheel. It is desirable to provide for the adjustment of the saddles 32 longitudinally of the table 36, the saddle nearest to the grinding wheel being adjustable to compensate for the reduction in diameter of said wheel due to wearing down thereof, while the other saddle is made adjustable to accommodate rods of varying lengths. There are occasions when the adjustment, particularly of the saddle nearest to the grinding wheel, should be very fine and gradual; therefore appropriate means for effecting such an adjustment are provided, and the example shown includes an adjusting screw 46' (see Fig. 6) arranged in screw-threaded engagement with a bracket 47 and with its inner end engaging the edge of a plate 48 upon which rests the left of lowermost end of the table 36.

The bracket 47 has a pair of spaced depending ears 49 (see also Fig. 2) that are slotted at 50 to straddle a shaft 51, the latter being supported in upstanding bearings 52 on the frame 3.

The ears 49 are separated sufficiently to provide stability for the bracket 47 upon said shaft and also to provide room for the nut of a bolt 53 by means of which said bracket is adjustably secured to the plate 48 and to the table 36 permitting said table and plate to be moved by the screw 46 longitudinally of said table and to be secured in its adjusted relation to the bracket 47. The ears 49 are elongated and the slots 50 are open at their lower ends to provide for vertical movement of the end of the table 36 to which said bracket is secured as for example when it is desired to suddenly remove the work from contact with the grinding surface of the wheel.

The shaft 51 is provided adjacent the bear-

ing 52 with cams or eccentrics 54 arranged to engage the plate 48 and an operating lever 55 is attached to one end of said shaft whereby said shaft may be rotated when it is desired to raise the end of said work table 70 and remove the ends of the rods that are being pointed, from the grinding wheel, said cams or eccentrics constituting the pivots for the lower end of said work table when the latter is angularly adjusted by the means 75 hereinafter to be described for adjusting the upper end thereof.

When a more extensive movement of the saddles than is possible with the screw 43 is required the screws 43 and 46 may be removed and the saddle and key 38 slid along the groove 39, said screws being inserted in other holes provided in the top of the work table.

The right-hand end of the table 36, as viewed in Fig. 3, is also adjustable vertically herein by means of screw-threaded rods 56 pivotally attached at 57 to the under side of said table, said pivots 57 constituting an axis about which the table is rocked by the eccentrics 54, the lower ends of said screws engaging plates 58 wherein they are held in their adjusted positions by check nuts 59 (see Figs. 3 and 4). The plates 58 are adjustably secured by screws 60 to brackets 61 mounted at opposite corners of the frame of the machine; said brackets being provided with a plurality of holes 62 to receive said screws 60 when it is desired to vary the positions of the screw-threaded rods 56. The plates 58 are also slotted at 63 to receive the screws 60 and to permit a limited adjustment of the plates without necessitating the movement of the screws 60 to other holes 62.

From the foregoing description it will be seen that a universal adjustment of the table 36 is possible.

In machines of the type shown considerable difficulty has been experienced in feeding rods to the grinding wheel by reason of the fact that rods of considerable length become twisted about each other but in the present machine this has been overcome by providing a plurality of sets of feed members, each including a saddle and feeding wheel and arranged for independent adjustment longitudinally of the work table, as previously described, so that they may engage the rods at such points as to prevent any twisting or entangling of said rods.

The feed wheels 33 as well as the saddles 32 are independently adjustable, said wheels being mounted upon a shaft 64 journalled to rotate in boxes 65 vertically adjustable in slotted standards or brackets 66, the latter being secured to the upper surface of the table 36. The wheels 33 are keyed to said shaft but are capable of movement longitudinally of said shaft and are adapted to be secured thereto in their adjusted posi-

tion by screws 67. The shaft 64 receives its motion from the counter-shaft 68 carried by one of said standards 66 and through the worm 69 and worm gear 70, the latter being secured to the end of the shaft 64.

The counter-shaft 68 is provided with a pulley 71 which is driven from any suitable source of power by a belt 72. The belt 72 preferably is arranged to lead from the pulley 71 upward at least for a short distance and when the left-hand end of the table 36 as viewed in Fig. 3, is raised by the cams 54 and the operating lever 55, said belt 72 is slackened just enough to prevent further movement of the shaft 68, thus stopping the feed of the rods to the grinding wheel.

It is often necessary to adjust the feed wheels 33 toward or away from the guiding surfaces of the saddles 32 especially when rods of larger or smaller diameter are to be fed and obviously it is desirable that the two or plurality of said wheels 33 be given simultaneous and equal movements so that the same amount of pressure will always be brought to bear upon the rods where they engage the saddle nearest the grinding wheel as well as with the other set, thus insuring an equal feeding movement at opposite ends of the rod. For this purpose means are provided for raising and lowering both ends of the shaft 64 at the same time and an equal amount, said means comprising screws 73, one being rotatable in each of the standards 66 and having screw-threaded engagement with the boxes 65. To the upper end of the screws 73 are attached bevelled gears 74 which mesh with bevelled gears 75 secured to a common driving shaft 76 journalled to rotate in bearings in said standards. A hand wheel 77 is attached to said shaft 76 and serves as means for manually operating the shaft to raise and lower said boxes.

While I have herein shown and described merely for illustrative purposes, a specific embodiment of my invention and have disclosed and discussed in detail the construction and arrangement incidental to such disclosures, it is distinctly to be understood that the invention is limited neither to the mere details or relative arrangement of parts nor to the specific application herein shown but that extensive variations from the illustrations may be made without departing from the principles thereof.

Claims.

1. In combination, a work member, a housing substantially enclosing said work member, bearings in said housing within which said work-member is journalled to rotate and means to raise and lower said housing together with said work member.

2. In combination, a work table, a work member, a housing within which said grind-

ing wheel is journalled to rotate, means to raise and lower said housing together with said work member relatively to said work table, and during said raising and lowering movements to maintain the axis of said work member in predetermined relation to said work table, and means independent of said raising and lowering means to tilt said housing and said axis.

3. A machine of the character described comprising, in combination, a work member and a housing within which said work member is journalled to rotate and arranged for bodily movement therewith, said housing having a peripheral opening above the axis of said work member for permitting work to be placed against the periphery of said work member.

4. A machine of the character described comprising, in combination, a frame, a work support mounted upon said frame, a grinding wheel to operate in conjunction with said work support, means to enclose said grinding wheel and provided with bearings within which said wheel is journalled to rotate, and means simultaneously to raise and lower said bearings with said housing and grinding wheel relatively to said work support.

5. A machine of the character described comprising, in combination, a rotatable work-forming member, means to feed the work transversely of the working face of said work-forming member, and means to raise and lower said work-forming member bodily with respect to the work-feeding means and to maintain the axis of said work-forming member in parallel relation with predetermined former positions thereof.

6. In a machine of the character described, the combination of a frame comprising side members, a housing arranged for vertical sliding movement between said side members, a work member journalled to rotate in said housing, adjustable guiding means for said housing, and means to raise and lower said housing together with said work member relatively to said side members.

7. A machine of the character described, comprising, in combination, a frame, a housing arranged within said frame for bodily movement, a grinder rotatably arranged within said housing, means bodily to move said housing together with said grinder relatively to said frame, and to maintain the axis of said grinder parallel with its previous positions, and means to secure said housing to said frame in its adjusted position.

8. A rod pointing machine comprising, in combination, a work wheel, a housing within which said work wheel is journalled to rotate, means to move the axis of said work wheel to positions parallel with its previous position to compensate for wear of said

work wheel, and a guard to prevent discharge of dust from said housing, said guard having an edge conforming to the working face of said work wheel adapted to be moved to compensate for wearing down of said wheel. 65

9. A rod pointing machine comprising, in combination, a grinding wheel, a housing within which said grinding wheel is arranged to rotate, said housing having an opening in its upper portion to permit the work to be placed against the periphery of said wheel, means to feed the work transversely of the face of said wheel, and means, 70 bodily to move said housing together with said wheel vertically with respect to the work feeding means to compensate for wear of said wheel, said housing moving means being adapted to maintain the axis of said 75 wheel during said movements parallel with predetermined previous positions thereof. 80

10. A grinding machine comprising, in combination, a rotary grinder, a housing within which said grinder is arranged to rotate, means to feed the work to said grinder, and means bodily to raise and lower said housing together with said grinder with respect to the work, said raising and lowering means including screws attached to opposite sides of said housing, nuts to rotate in screw-threaded engagement with said rods to effect axial movement of said rods, and common rotating means for said nuts. 90

11. A grinding machine comprising, in combination, a rotary grinder, a housing within which said grinder is arranged to rotate, means to feed the work transversely of the face of said grinder, means bodily to raise and lower said housing together with said grinder with respect to said work-feeding means, said raising and lowering means including screws pivotally attached at separated points to said housing, toothed nuts to rotate in screw-threaded engagement with said screws, and common rotating means for said nuts to effect the uniform raising and lowering of said rods. 100

12. A grinding machine comprising, in combination, a rotary grinder, a shaft to which said grinder is secured, a housing to enclose said grinder, said housing having bearings at opposite sides thereof within which said shaft is journaled to rotate, means to effect simultaneous adjustment of said bearings with said housing, and means to secure said housing in its adjusted position. 110

13. A grinding machine comprising, in combination, a rotary grinder, a casing having bearings at opposite sides to support said grinder, means bodily to move said grinder and said casing and means connected with said housing to remove dust therefrom. 120

14. A grinding machine comprising, in

combination, a rotary grinder, a casing to enclose said grinder, means bodily to move said grinder and said casing, and means connected with said housing to remove dust therefrom arranged to compensate for variations in the movement of said housing. 125

15. A grinding machine comprising, in combination, a grinding wheel, a housing within which said grinding wheel is arranged to rotate, said housing having a peripheral opening to permit the work to be placed in contact with the wheel, a guard plate adjustably secured to said housing adjustment to the face of said wheel to prevent the discharge of dust from said housing and means connected with said housing to remove the dust therefrom. 135

16. A point forming machine comprising, in combination, a forming member and means to feed the work to said forming member including a plurality of spaced work guiding members having concave guiding surfaces, and feed wheels having work faces coextensive in width with and respectively to coact with the guiding surfaces of said work guiding members. 140

17. A rod pointing machine comprising, in combination, a grinding member having a concave grinding face and a plurality of cooperating opposed work-feeding members to engage the work at spaced points and to effect the rolling of said work transversely of and in contact with said concave guiding face. 145

18. A rod pointing machine comprising, in combination, a grinding member having a concave grinding face and a plurality of sets of equal faced resilient work-feeding members to engage the work at predetermined spaced points and to effect the rolling of said work transversely of said concave grinding face. 150

19. A rod pointing machine comprising, in combination, a grinder, a plurality of sets of feed members independently adjustable longitudinally of the work adapted to roll said work transversely of the face of said grinding member, and means simultaneously to adjust the members of said sets toward and from each other. 155

20. In combination, a grinding wheel, a table mounted adjacent to said wheel, means to vary the angle of said table relatively to said wheel, a plurality of saddles carried by said table and independently adjustable thereon relatively to said wheel, and feed wheels respectively to cooperate with said saddles to roll rods transversely of the grinding face of said grinding wheel. 160

21. In combination, a grinding wheel, a table mounted adjacent to said wheel, means to vary the angle of said table relatively to said wheel, a plurality of saddles carried by said table and independently adjustable

thereon relatively to said wheel, a shaft journalled to rotate in bearings on said table, a plurality of feed wheels adjustably secured to said shaft to cooperate respectively with said saddles to feed rods to said grinding wheel, and means simultaneously and uniformly to adjust opposite ends of said shaft relatively to said table to vary the positions of said feed wheels with respect to said saddles.

22. In combination, a grinding wheel, a table universally adjustable in relation to the periphery of said grinding wheel, a plurality of saddles arranged upon said table, said saddles having concave resiliently covered guiding surfaces, feed wheels respectively to cooperate with said saddles to feed rods transversely of the face of said grinding wheel, and means for moving said table bodily whereby the angle of the rod to said wheel may be varied.

23. A rod grinding machine comprising, in combination, a grinder, a table arranged for transverse adjustment and for independent vertical adjustment of the opposite ends thereof relatively to said grinder, and means carried by said table to feed the work to said grinder.

24. A rod grinding machine comprising, in combination, a grinder, a work-supporting table pivotally arranged relatively to said grinder, means for swinging said table about its pivotal axis to remove the work from contact with said grinder, and means vertically to adjust said axis.

25. In combination, a grinder, a work supporting table pivotally supported at opposite ends to permit angular adjustment relatively to said grinder, and means vertically to adjust the pivots for said table.

26. In combination, a grinder, a pivotal table, work-feeding means carried by said table including a pair of saddles independently adjustable on said table and feed wheels to cooperate with said saddles to roll

the work along the surface thereof, transversely of the face of said grinder.

27. In combination, a grinder, a work table, work-feeding means carried by said table including a plurality of independently adjustable saddles, feed wheels having independent axial adjustment adapted to cooperate respectively with said saddles to roll the work along the surface thereof transversely of the face of said grinder, and means for uniformly adjusting said feed wheels relatively to said saddles.

28. In combination, a work member, a plurality of independently adjustable work guiding members and rotary feed members to cooperate respectively with said work guiding members to guide the work to said work member.

29. In combination, a work member, a plurality of independently adjustable resilient faced concave work guiding members and rotary feed members to cooperate respectively with said work guiding members to guide the work to said work member.

30. In combination, a work member and means to feed work to said member including a plurality of separated work guiding members and rotary feed members to cooperate respectively with said work guiding members, the work-engaging faces of said feed members being substantially the same width as the work-engaging faces of said work guiding members.

31. In combination, a work member and means to feed work to said member including a plurality of separated work guiding members and rotary feed members to cooperate respectively with said work guiding members, said work guiding and work feeding members having resilient work-engaging faces.

In testimony whereof, I have signed my name to this specification.

JONATHAN A. HUNT.
